UNITED STATES PATENT OFFICE.

HARRY L. KENYON, OF SETAUKEET, NEW YORK.

DESIGN FOR A TIRE-TREAD.

56,975.

Specification for Design.

Patented Jan. 25, 1921.

Application filed August 2, 1920. Serial No. 400,868. Term of patent 14 years.

To whom it may concern:

Be it known that I, HARRY L. KENYON, a citizen of the United States of America, residing at Setauket, in the county of Suffolk and State of New York, have invented a new, original, and ornamental Design for a Tire-Tread, of which the following is a specification, reference being had to the accompanying drawing, forming a part thereof.

Figure 1 is a detail plan view showing the tread.

Fig. 2 is a perspective view showing a section of the tire with the tread therein.

I claim:

The ornamental design for a tire tread, substantially as shown.

HARRY L. KENYON.
